UNITED STATES PATENT OFFICE.

JOSEPH PAUL, OF EAU CLAIRE, WISCONSIN, ASSIGNOR OF ONE-HALF TO ALBERT PAUL, OF MILWAUKEE, WISCONSIN.

WORKBENCH.

Application filed June 4, 1923. Serial No. 343,316.

To all whom it may concern:

Be it known that I, JOSEPH PAUL, a citizen of the United States, residing at Eau Claire, in the county of Eau Claire and State 5 of Wisconsin, have invented a new and useful Workbench, of which the following is a specification.

This invention relates to benches, and more particularly work benches especially 10 designed for carpenters' use, the primary object of the invention being to provide a foldable work bench capable of being folded into a small and compact article to permit the same to be transported with facility.

Another object of the invention is to provide a novel form of vise wherein the jaws 15 of the vise will be forced into clamping relation with respect to each other when pressure is brought to bear on the top or working surface of the bench.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawings:

Figure 1 is a perspective view of a work bench constructed in accordance with the invention.

Figure 2 is an elevational view thereof.

Figure 3 is a front elevational view of a work bench.

Figure 4 is an end elevational view of a bench in its folded position.

Figure 5 is a sectional view taken on line 5-5 of Figure 3.

Figure 6 is an enlarged fragmental sectional view of the table top disclosing the outer jaw supporting bar of the vise and hangers for supporting the same.

Referring to the drawings in detail, the bench includes a top 5 to which the front bar 6 is secured, the front bar 6 constituting one of the jaws of the vise to be hereinafter more fully described.

The bench also includes supporting legs which are disposed at the respective ends of the bench, the supporting legs comprising pivotally connected members 8 that have

their upper ends pivotally connected to the 55 vertical supporting bars 9, at 10, the bars 9 being secured to the bars 6 and 7 at points adjacent to the ends thereof.

The lower ends of the supporting bars 9 are disposed adjacent to the leg members 8 60 and have connection therewith, through the tubular members 11 and rods 12 that move within the tubular members 11, the tubular members having rigid connection with the supporting bars 9 at 13, the opposite ends 65 of the tubular members being held to the bars 9 by means of the eye bolts 14.

The rods 12 are pivotally connected to the members 8 at 15, the rods having right angled extremities passing through the 70 brackets 16 that are carried by the members 8. At the lower ends of the rods 12 are coiled springs 12' that provide abutments for the tubular members 11 to restrict movement of the tubular members. Cooperating 75 with the bar 6 is a jaw 17 designed to clamp an article to the bench.

The bar 17 is supported at one of the ends of the respective bars 18, the opposite ends of the bars 18 being hingedly connected to the board 19, at 20, the board 19 being secured to the bar 7. Depending from the under surface of the forward board 21 that forms a part of the bench top 5 are swings 22 that support the bars 18 at points adjacent to the forward ends thereof, the connection between bars 18 and the top being such as to permit of movement of the bars 18 with respect to the top 5, to move the members 6 and 17 towards and away from each other to accomplish the clamping result.

Thus it will be seen that since the bars 18 are pivotally connected to the member 7 and the member 6 carried by the members 9 that when the members 9 on opposite sides 95 of the bench are brought towards each other, the member 17 is moved away from the front bar 6, to the end that an article may be positioned therebetween and clamped in such position when pressure is brought to 100 bear on the table. The clamping is accomplished by the upper ends of the members 8 moving away from each other.

In order that the forward section 21 may 105 move with respect to the main portion of the bench top 5, hinges 23 are provided for connecting the members 5 and 21. At one end of the bench 5 is a supporting block 24 pro-

viding a rest for the extension 25 of the end board 26 that is employed for lengthening the bench top 5.

Formed in the end section 26 are a plurality of spaced openings 27 that are adapted to accommodate the adjustable stop 28 employed as an abutment to be engaged by one end of a board under operation.

At the rear of the bench is supported a ladder indicated at 29, which ladder includes forward extended supporting bars 30 provided with openings accommodating the supporting rod 31 that has its ends positioned in suitable openings formed in the leg members 8 as shown by Figure 1 of the drawings.

A chain 32 connects the ladder with the forward ends of the bars 30 so that movement of the ladder with respect to the bars 30 will be restricted. When the ladder is moved to its folded position, the ladder contacts with the board 33 secured to the blocks 34 that have connection with the opposed leg members 8.

When it is desired to fold the bench in a manner as shown by Figure 4 of the drawings, the upper ends of the members are moved towards each other, and since the top 5 is carried by the upper ends of the leg members 8 at the left side of the bench, viewing the bench from one end thereof as shown by Figure 5, the top will hinge downwardly to a position as shown by Figure 4, while the members 18 will swing to positions as shown by Figure 4, due to the hinged connection at 20, to the member 19 which is carried at the rear of the bench.

The step ladder which is shown as forming a part of the work bench is designed to permit the use of the work bench as a ladder, should it be desired to reach onto shelves which are usually positioned above work benches.

From the foregoing it will be seen that I have provided a work bench which may be readily and easily folded into a small and compact article to facilitate the trans-

portation of the same, and at the same time provided a vise built in the bench proper.

What I claim as new is:—

1. A work bench including leg sections pivotally connected at points intermediate their ends, a bench top including a forward section, and including a board hingedly connected to the forward section, said forward section constituting a vise jaw, a movable jaw section cooperating with the first mentioned jaw section to clamp an article to the bench, and supporting bars for supporting the movable jaw section. 50

2. A work bench including foldable leg sections, a hinged top supported at the upper ends of the leg sections, a stationary vise section at one side of the top, a movable vise section, bars supported by the leg sections, swings on the movable vise section and adapted to support the movable vise section, and resilient means for holding the foldable leg sections in their extended positions. 60

3. A work bench including foldable leg sections, a hinged top supported at the upper ends of the foldable leg sections, bars extending downwardly from the top, tubular members supported by the bars, rods 75 extending into the tubular members and having connection with the leg sections, and means at the lower ends of the rods and adapted to engage the lower ends of the tubular members to restrict movement of 80 the top.

4. A work bench including leg sections, pivotally connected at points intermediate their ends, a top hingedly connected to the leg sections, a front bar forming a part of the top and constituting a vise jaw, said vise jaw adapted to move with the top, and a stationary member adapted to cooperate with the bar to grip articles therebetween. 85

In testimony that I claim the foregoing 90 as my own, I have hereto affixed my signature.

JOSEPH PAUL.
